ULTRA HIGH FREQUENCY MIXER CIRCUIT

Adelbert van Weel, Eindhoven, Netherlands, assignor to Hartford National Bank and Trust Company, Hartford, Conn., as trustee

Application February 12, 1947, Serial No. 728,144
In the Netherlands August 8, 1944

Section 1, Public Law 690, August 8, 1946
Patent expires August 8, 1964

7 Claims. (Cl. 250—20)

1

This invention relates to a circuit arrangement for the transmission of electrical ultrahigh-frequency oscillations, in which one oscillation (push-pull oscillation) may occur in push-pull between a pair of corresponding electrodes of two discharge systems and a second oscillation (in-phase oscillation) may occur in phase coincidence between the said electrodes and a point of fixed potential either simultaneously or alternately with the push-pull oscillation. An example of such a circuit is a push-pull mixing circuit for ultrahigh-frequency oscillations, in which the received oscillations are supplied in push-pull and the local oscillations are supplied in phase coincidence to the input electrodes of two mixing systems.

In a circuit arrangement of the above-mentioned kind an oscillatory circuit (push-pull circuit) tuned to the push-pull oscillation will, as a rule, be connected in push-pull between the said corresponding electrodes. It has been suggested to provide also one or more circuit elements common to the circuits of the corresponding electrodes, which elements constitute, jointly with the push-pull circuit, an oscillatory circuit tuned to the in-phase oscillations. This affords the advantage that the discharge systems may be back-coupled in such manner that oscillations are produced in the in-phase circuit.

In a push-pull mixing circuit the push-pull circuit, for example, is tuned to the received oscillations and the in-phase circuit is tuned to the local oscillations, while means may be provided whereby the mixing systems are so back-coupled as to produce themselves the in-phase local oscillations. If the circuit is used also for transmitting purposes, the back-coupling may also be effected in such manner that the push-pull oscillation is produced, which can then be transmitted directly by the receiving aerial. Furthermore, similar circuits have been suggested in which the functions of the push-pull circuit and of the in-phase circuit have been exchanged.

In the above-mentioned circuit arrangements it is frequently desirable that either the frequencies of the produced oscillations (the local oscillations and/or the oscillations to be transmitted) should be stabilised, or the input circuits (push-pull circuit, in-phase circuit) should be made very selective.

The present invention purports to provide a circuit arrangement in which the above-mentioned requirements as regards stability and selectivity can be fulfilled in a simple and efficacious manner.

2

According to the invention, the tuning of the circuit to the push-pull oscillation and to the in-phase oscillation is stabilised by means of one cavity resonator (for example a box circuit).

5 Use is preferably made of a box circuit comprising two inner conductors arranged symmetrically, the said corresponding electrodes of the two discharge systems each being connected to one of the inner conductors and two mutually connected electrodes of the two discharge systems being connected to the wall of the box circuit.

For an efficacious tuning and control of the box circuit an adjustable concentrated capacity is arranged between the inner conductors, and a star connection of adjustable concentrated capacities is arranged between the inner conductors and the wall of the box circuit.

10 The invention will be explained more fully by reference to the accompanying drawing showing, by way of examples, two embodiments thereof.

15 Fig. 1 shows a transmitting-receiving circuit in which a dipole aerial 1', 1'' is used for both the reception and the transmission of oscillations. When used as a receiving aerial, the received oscillations are transmitted in push-pull connection, via a Lecher line 2', 2'', to the cathodes of two mixing triodes 3', 3''. The Lecher line 2', 2'' constitutes a push-pull circuit which may be tuned to the frequency of the received oscillations by means of a short-circuit bridge. The latter is connected to earth via an adjustable impedance 4. The control grids of the two mixing triodes are jointly connected to earth through an adjustable impedance 5. The in-phase circuit 20 constituted by the series-connected impedances 4 and 5, the impedances connected pairwise in parallel of the two halves of the push-pull circuit, and the parallel-connected input impedances of the two mixing triodes is tuned to the frequency of the local oscillations. By a suitable adjustment of the impedances 4 and 5 it may be achieved, in addition, that the aerial 1', 1'' is located in a voltage minimum of the local oscillations.

25 30 35 40 45 50 55 The intermediate-frequency voltage in the circuit may be taken from terminals indicated by 6. These terminals are connected to the anodes of the triodes 3', 3'' through choke coils 7', 7'' and two adjustable impedances 8', 8''. The choke coils 7', 7'' serve to avoid a transmission of the high-frequency oscillations to the parts of the receiver following the mixing stage. The junction of the impedance 8' and the choke coil 7', and the junction of the impedance 8'' and the choke coil 7'' are each connected to a box circuit 9,

which will be described in detail hereinafter. The outer wall of this box circuit is earthed. The triodes 3' and 3'' may advantageously be housed together in one tube and, if desired, may be provided with a common cathode.

The presence of the impedances 5, 8', 8'' and 9 has the effect of producing a feed-back coupling whereby the damping of the push-pull oscillatory circuit 2', 2'' as well as of the said in-phase circuit may be reduced, provided that the said impedances are adjusted to a correct value. This feed-back coupling may be enhanced to such extent that there are produced either oscillations of a frequency corresponding to the frequency to which the push-pull oscillatory circuit is tuned and which oscillations may be transmitted directly by the receiving aerial 1', 1'', or oscillations whose frequency corresponds to the frequency to which the in-phase circuit mentioned before is tuned and which oscillations therefore may be used as the local oscillations in the reception. It is even fundamentally possible to produce simultaneously the oscillations to be transmitted and the local oscillations serving for the reception, so that a transmission and a reception can take place, and if desired simultaneously, without any switching-over operation. As a rule, however, it is desired to produce only one of the two oscillations. In this case one or more of the feed-back impedances may advantageously be made inoperative by short-circuiting, or as an alternative damping resistances may be included in one of the circuits, (push-pull circuit, in-phase circuit), the construction being such that the production of either local oscillations or oscillations to be transmitted is avoided.

Now, according to the invention, the frequency of the oscillations to be transmitted and the frequency of the local oscillations are both established by the use of the box circuit 9 which has been mentioned before. This box circuit comprises two inner conductors 10' and 10'' arranged symmetrically, together with four adjustable concentrated capacities 11, 12', 12'' and 13. The box circuit has two tunings, viz, one as the push-pull circuit and the other as the in-phase circuit. By regulating the capacity 11 it is possible to vary the frequency of the push-pull circuit, whereas the frequency of the in-phase circuit may be adjusted by regulating the capacity 13. With the aid of the capacities 12' and 12'' a correct symmetrical arrangement may be obtained. The anodes of the mixing systems are connected to the box circuit in points A' and A'', the extent to which the mixing systems are coupled to the box circuit being in the first place dependent on the places of the points A' and A'' and further on the values of the impedances 5, 8' and 8''. Since, as a rule, the places of the points A' and A'' are fixed once for all, the adjustment of the coupling is effected solely with the aid of the said impedances. By a suitable choice of these impedances it is possible for the coupling of the mixing systems with the box circuit to be adjusted differently for each of the modes of oscillation, owing to which the extent of stabilisation obtained for the push-pull circuit is different from that for the in-phase circuit.

Indeed, if the impedances 8' and 8'' have a capacitative value, the coupling is made less strong for both modes of oscillation, from which results a better stabilisation. If, however, the impedances 8' and 8'' assume an inductive value, the coupling becomes stronger and the stabilisation becomes less satisfactory.

If the impedance 5 is given a capacitative value, only the coupling for the in-phase oscillation becomes less strong and hence the stabilisation becomes better (with an inductive value of the impedance 5 the coupling becomes stronger, etc.). The extent of stabilisation of the two kinds of oscillation may therefore be fully controlled by a suitable choice of the three said impedances.

Fig. 2 shows a circuit arrangement for receiving electrical ultrahigh-frequency oscillations in which in a similar manner use is made of a box circuit as in the circuit shown in Fig. 1. In this case, however, the box circuit is used to improve the selectivity of the push-pull input circuit. For this purpose the dipole aerial 1', 1'' is connected in points B' and B'' to the inner conductors 10', 10'' of the box circuit, whereas the control grids of the mixing triodes 3', 3'' are connected in points C' and C'' to the said inner conductors.

As before, the local oscillations are produced by the circuit itself and this owing to the back-coupling by means of an inductance coil 14, located between the junction of the two cathodes and the junction of two condensers 15' and 15'' interposed between the anodes of the mixing systems 3' and 3''. The frequency of the local oscillations is now stabilised in a similar manner as in the circuit of Fig. 1, even if the box circuit 9 is located between the control grids and the cathodes and not between the anodes and the control grids of the mixing triodes.

Instead of connecting the aerial directly to the box circuit in the points B', B'', it is also possible for the aerial to be connected, through small capacities, to the control grids of the two tubes.

In a circuit which utilizes a box circuit to enhance the selectivity of the input circuit, the box circuit may alternatively be arranged between the anodes as in the circuits shown in Fig. 1. However, use is preferably made of a circuit arrangement of the kind shown in Figure 2.

What I claim is:

1. A mixing circuit for combining local oscillations with high frequency oscillations comprising a pair of electron discharge tubes having first and second input electrodes and an output electrode, one pair of corresponding input electrodes being interconnected, an input circuit connected between the other pair of corresponding electrodes for applying the high frequency oscillations thereto in push-pull relation, an auxiliary circuit connected between said interconnection and the electrical center of said input circuit for applying local oscillations to said other pair of corresponding electrodes to cophasal relation, an output circuit connected between the output electrodes of said tubes for deriving the intermediate oscillations therefrom, and means to stabilize the mixing circuit for said local and high frequency oscillations, said stabilizing means including an enclosed tubular outer conductor, a pair of symmetrically disposed inner conductors connected to one end of said outer conductor, said outer conductor being connected to an intermediate point in said auxiliary circuit, means connecting said inner conductors respectively to the anodes of said tubes, a capacitance between said inner conductors having a value effecting resonance at the frequency of said high frequency oscillations and a capacitance between said inner conductors and said outer conductor having a value effecting resonance at the frequency of local oscillations.

2. An arrangement, as set forth in claim 1, wherein said capacitance between said inner

conductor and said outer conductor is constituted by a pair of series-connected capacitors connected between the free ends of said inner conductors, and a capacitor connected between said outer conductor and the juncture of said series-connected capacitors.

3. A mixing circuit for combining local oscillations with high frequency oscillations to produce intermediate frequency oscillations comprising a pair of electron discharge tubes each having a cathode, a grid and an anode, means interconnecting said grids, a resonant input circuit tuned to the high frequencies oscillations and connected between the cathodes of said tubes for applying said oscillations thereto in push-pull relation, a first impedance connected between the electrical center of said input circuit and ground, a second impedance connected between said interconnection and ground, said first and second impedances in combination with said input circuit being tuned to the frequency of the local oscillations for applying same to said tubes in cophasal relation, an output circuit connected between said anodes for deriving the intermediate frequency oscillations therefrom, and means to stabilize the mixing circuit for said local and high frequency oscillations including an enclosed tubular outer conductor, a pair of symmetrically disposed inner conductors connected to one end of said outer conductor, said outer conductor being connected to ground, means connecting said inner conductors respectively to the anodes of said tubes, a capacitance between said inner conductors having a value effecting resonance at the frequency of said high frequency oscillations and a capacitance between said inner conductors and said outer conductors having a value effecting resonance at the frequency of said local oscillations.

4. An arrangement, as set forth in claim 3, wherein said second impedance has a value effecting positive feedback for said local oscillations to reduce the damping of the cophasal circuit.

5. An arrangement, as set forth in claim 3, further including an impedance element between each of said anodes and said output circuit, said elements having values effecting positive feedback for said high frequency oscillations to reduce the damping of the push-pull circuit.

6. An arrangement, as set forth in claim 3, further including a pair of impedance elements each interposed between one of said anodes and one of said inner conductors, said elements having values effecting positive feedback for said high frequency oscillations to produce self-oscillation in the push-pull circuit.

7. A transceiver system for mixing local oscillations with high frequency oscillations to produce intermediate frequency oscillations and for

transmitting high frequency oscillations, said system comprising a pair of electron discharge tubes each having a cathode, a grid and an anode, means interconnecting said grids, a resonant input circuit tuned to the high frequencies oscillations and connected between the cathodes of said tubes for applying said oscillations thereto in push-pull relation, a first impedance connected between the electrical center of said input circuit and ground, a second impedance connected between said interconnection and ground, said first and second impedances in combination with said input circuit being tuned to the frequency of the local oscillations for applying same to said tubes in cophasal relation, an output circuit connected between said anodes for deriving the intermediate frequency oscillations therefrom, means to stabilize the mixing circuit for said local and high frequency oscillations including an enclosed tubular outer conductor, a pair of symmetrically disposed inner conductors connected to one end of said outer conductor, said outer conductor being connected to ground, means connecting said inner conductors respectively to the anodes of said tubes, a capacitance between said inner conductors having a value effecting resonance at the frequency of said high frequency oscillations and a capacitance between said inner conductors and said outer conductor having a value effecting resonance at the frequency of said local oscillations, said second impedance having a value effecting positive feedback for said local oscillations to reduce the damping of the cophasal circuit, and a pair of impedance elements each interposed between one of said anodes and one of said inner conductors, said elements having values effecting positive feedback for said high frequency oscillations to generate oscillations in the push-pull circuit.
